The ornamental design for a display screen with a transitional graphical user interface, as shown and described.

DESCRIPTION

FIG. 1 is a front view of the first image in the sequence for a display screen with a transitional graphical user interface showing our new design;

FIG. 2 is the second image thereof;

FIG. 3 is the third image thereof;

FIG. 4 is the fourth image thereof; and,

FIG. 5 is the fifth image thereof.

The appearance of the transitional image sequentially transitions between the images shown in FIGS. 1-5. The process or period in which one image transitions to another image forms no part of the claimed design.

The broken line showing of a display screen, windows, images, words, and letters represents environment and forms no part of the claimed design.
